UNITED STATES PATENT OFFICE.

HENRY B. KEIPER, OF LANCASTER, PENNSYLVANIA.

DESIGN FOR A STAND FOR ROTARY BLOWERS AND FORGES.

SPECIFICATION forming part of Design No. 34,881, dated July 30, 1901.

Application filed June 10, 1901. Serial No. 64,048. Term of patent 14 years.

To all whom it may concern:

Be it known that I, HENRY B. KEIPER, a citizen of the United States, residing at Lancaster, in the county of Lancaster and State of Pennsylvania, have invented and produced a certain new, useful, and original Design for Stands for Rotary Blowers and Forges; and I do hereby declare the following to be a full, clear, and exact description of the invention, such as will enable others skilled in the art to which it appertains to make and use the same.

In the accompanying drawing, which forms a part of this specification, I have illustrated a perspective view of a stand for a rotary fan-blower embodying my new design.

As shown in the drawing, the leading or material feature of my design consists of a series of bent tube-like legs A, flaring outwardly from a point near their lower ends to afford a wide base, and extending thence up-

wardly in substantially parallel planes and supporting at their upper ends a headpiece B, which is provided with pendent bosses b on its under side, having a socket-like or tubular appearance, the upper ends of said legs 25 appearing to be inserted in said sockets, and said headpiece also having a vertically-disposed aperture or opening therein.

Having thus described my invention, what I claim as new, and desire to secure by Letters 30 Patent of the United States, is—

The design for a stand for rotary blowers and forges, substantially as shown and described.

In testimony whereof I affix my signature 35 in presence of two witnesses.

HENRY B. KEIPER.
